GAS ENGINE FUEL ECONOMIZER

Erwin G. Baker, Indianapolis, Ind.

Application June 12, 1941, Serial No. 397,655

4 Claims. (Cl. 257—235)

This invention relates to automotive engines and particularly to means for conditioning fuel being supplied the engines while running, and a primary object of the invention is to achieve a far greater fuel economy than has heretofore been obtained in the ordinary stock engines without having to change any of the engine structure. A still further important object of the invention is to provide such fuel economizing means that may be installed directly on the stock engine without in any way having to change the fuel manifolding or the carburetor other than reducing the size of the jets or metering pins therein. A still further important object of the invention is to provide means not only achieving great fuel economy but at the same time causing the engine to operate at a much lower coolant temperature.

These and other important objects of the invention, such as the relatively low cost of the economizing means, the simplicity of its construction, and its service as a partial or even complete muffler in conjunction with its primary object of fuel economy, will become apparent to those versed in the art in the following description of one particular form of the invention as illustrated in the accompanying drawings, in which

Fig. 1 is a view in central, vertical, longitudinal section through a structure embodying the invention;

Fig. 2, a view in horizontal section on the line 2—2 in Fig. 1; and

Fig. 3, a view in end elevation with an end wall partially broken away.

Like characters of reference indicate like parts throughout the several views in the drawings.

In the particular form of the invention as herein shown, a housing 10 is constructed in the form of a hollow cylinder with ends 11 and 12, through which are provided respectively intake and discharge ports within the respective outwardly turned annular flanges 13 and 14 positioned axially of the housing 10 on those ends.

A length of tubing 15 has an intake end inserted through an opening in the top of the housing 10 at the intake end thereof and then is formed to curve around spirally within the housing 10, to have a discharge end carried downwardly through the lower side of the housing 10, herein shown as extending on through the housing 10 to project within a discharge nipple 16 that is fixed to the under side of the housing 10 to extend therebelow. The discharge end of the tubing 15 is positioned approximately at the center portion of the housing 10. A second tubing 17 has its intake end inserted within an opening in the top of the housing 10 immediately adjacent the end of the tube 15 in circumferential spacing therefrom. This second tube 17 is carried within the housing 10 and curved around in a spiral form within the turns of the tube 15, preferably removed from contact therewith, and

then has its discharge end carried downwardly through the wall of the housing 10 to open into the nipple 16, circumferentially spaced from the discharge end of the tube 15.

The two tubes 15 and 17 thus defined and located within the housing 10 occupy substantially half of the space within the housing 10. The other half of the housing 10 toward the discharge end thereof contains therein the major length 10 of tube 18 and the minor length of tubing 19, corresponding to the tubes 15 and 17 respectively. The tube 18 has its intake end carried through an opening in the top side of the housing 10 adjacent the discharge end wall 12 and is fixed to the housing wall in any suitable manner, such as by welding, the ends of all of the tubes 15, 17, 18 and 19 being rigidly fixed in like manner to the wall of the housing 10.

From the intake end, the tube 18 is carried downwardly within the housing 10 and thence is curled around spirally to terminate by a discharge end carried downwardly and through the housing 10 toward the center thereof to have that discharge end within the nipple 16. In the same manner the intake end of the tube 19 is carried through the wall of the top side of the housing 10 circumferentially spaced from the end of the tube 18 and then is carried downwardly and curved around spirally within the coils of the tube 18 to terminate finally by a downturned discharge end carried through the bottom of the housing 10 to extend within the nipple 16. The positions of these terminating ends is best shown in Fig. 2.

On the top side of the housing 10 is mounted a support for the customary carburetor 20. In the form herein shown, this support consists of an inverted box-like structure 21 positioned over the top side of the housing 10 and welded thereto so as to form in effect a manifold connection between the intake ends of the respective tubes 15, 17, 18 and 19. Then this member 21 has an opening in its top side centrally positioned, and around which opening a mounting nipple 22 is fixed and formed to receive and carry the carburetor 20 thereon.

The nipple 16 is provided with a flange 23 conforming in shape and drilling to that of the flange 24 found on the customary intake manifold 25. Therefore the entire structure as above described, with the carburetor 20 mounted thereon, may be mounted directly on the intake manifold 25. In effect, the structure comprising the invention is simply inserted between the carburetor 20 and the manifold 25. The exhaust pipe leading from the engine (not shown) is connected directly to the nipple 13, and then a connection is made from the discharge nipple 14 to the usual line running to the engine muffler, or where the muffler is to be dispensed with, then directly to the tail pipe. In any event, the hot exhaust gases

of the engine carrying the manifold 25 are carried in their entirety through the housing 10 to be discharged through the nipple 14.

In order to retard the flow of the exhaust gases through the housing 10 to obtain a greater transfer of heat from those gases to the tubes within the housing 10, a center baffle 26 is mounted within the housing 10. In the form herein shown, it is a circular disk of metal having a diameter slightly less than the internal diameter of the housing 10. A plurality of legs 27 extend from the baffle 26 to bear normally against the inside of the housing 10 to serve as spacing members so as to locate the baffle 26 centrally of the housing 10, thereby leaving an annular space between the periphery of the baffle and the wall of the housing as an opening through which the gases must travel. Another baffle 28 is carried within the housing 10 adjacent the opening through the discharge nipple 14 to cause the exhaust gases to travel around its periphery before escaping through the discharge opening. This baffle 28 is herein shown as being mounted on a rod 29 that is fixed to a bar 30 crossing over the opening through the nipple 14. This rod 29 extends axially through the coils of the tubes 18 and 19 and through the central baffle 26 to engage therewith by any suitable means, such as by the nuts 31 and 32, one on each side of the baffle screw-threadedly engaging the rod 29. By means of these baffles 26 and 28, a better distribution of the exhaust gases is had within the housing 10 and hence there is a more complete transfer of heat from those gases to the tubes than would be had were the gases permitted to travel straight through the housing 10. This transfer of heat is further aided by the fact that the gases are caused to travel in a whirling path by reason of the spiral formation of the tubes. It is to be noted that the direction of the spiral of these tubes is reversed as between the sets of tubes on each side of the central baffle 26, thereby tending to set up a greater turbulence of the exhaust gases within the housing 10. Not only does the construction tend to extract all heat possible from the exhaust gases, but it also tends to silence the exhaust very materially and in some cases, the usual muffler may even be omitted in the exhaust gas line.

The internal diameter of the tubes 15, 17, 18 and 19 may vary of course, depending upon the size of the engine which in turn determines the required volume of intake gases, but in one particular form the invention as used to make considerable actual road tests, these tubes have been given an internal diameter of $\frac{5}{8}$ of an inch and a total length to give an internal area of some six square feet. It is desirable to heat these tubes and hence the gases traveling therethrough, to temperatures approaching 1000° F. Even at a temperature of 500° F., surprising results have been obtained by the use of the device on a car weighing over 4400 pounds in that an average of 32.2 miles per gallon of ordinary gasoline (not treated for anti-knock) was obtained in driving at an average speed of 38.2 miles per hour between Grand Canyon, Arizona, and the Gilmore Stadium, Los Angeles, California, a total distance of 599.6 miles.

While the invention has been herein shown and described in the one precise form, it is obvious that structural variations may be employed, such, for example, as the number of tubes employed, one within the other, the exact posi-

tioning of the intake and outlet of the tubes, and the interconnection between the carburetor and the intake ends of the tubes, and other minor details, all without departing from the spirit of the invention and it is therefore desired that the invention not be limited thereto beyond the limitations as may be imposed by the following claims.

I claim:

1. For mounting between an engine carburetor and an engine intake manifold, an exhaust conduit having opposite end exhaust intake and discharge openings, a plurality of tubes spirally curved around a common axis and positioned within said conduit, the intake ends of said tubes opening out through a side of said conduit, chamber means along said conduit having a floor in common therewith for interconnecting the discharge end of said carburetor with said tube intake ends at remote ends of said floor, and a fitting on said conduit receiving centrally of said remote ends in common the discharge ends of said tubes, said fitting being formed to connect and discharge into said intake manifold.
2. For an engine having a carburetor for mixing volatilized fuel with air and an exhaust gas collector, fuel economizing means comprising in combination a housing for end connection with said exhaust gas collecting means, said housing having an opposite end exhaust gas discharge opening and further having a fuel mixture intake opening centrally disposed on one side thereof; a wall within said housing forming a preheating and expansion chamber thereacross into which chamber said fuel mixture enters through said mixture intake opening, said wall being exposed to exhaust gases passing through the housing; separate fuel mixture closed conducting means leading from opposite end portions of said chamber into said housing, continuing therein toward the center thereof, and discharging through the side of the housing opposite said mixture intake opening; and a fuel mixture discharge conductor receiving in common the discharge from both of said mixture conducting means.
3. For a gas engine having a fuel volatilizing and air mixing carburetor and an exhaust gas manifold, fuel economizing means comprising an elongated housing through which exhaust gases from said manifold may pass from end to end; a chamber having a floor exposed to said gases within said chamber, said chamber having an intake opening opposite said floor to receive the fuel mixture from said carburetor, the projected floor area exceeding the area of said opening; fuel mixture conducting means leading respectively from opposite end zones of said chamber into respective exhaust gas intake and discharge ends of said housing and continuing through said housing to a central zone thereof; and fuel mixture, common discharge means receiving the discharge of said conducting means.
4. A fuel economizer comprising an elongated housing having an exhaust gas inlet at one end and an exhaust gas outlet at the other end; a fuel chamber carried along one side of said housing and having an intake opening opposite and centrally of said floor; a plurality of sets of tortuous confined gas passageways of relatively small cross-sectional area leading from remote zones of said chamber into said housing to the central zone thereof, to discharge therefrom externally of the housing; and a common external conductor receiving the discharge of said passageways.
